COAT RACK

Mark O. Uitz, Mountain View, Calif., assignor to F. J. L. Corporation, Palo Alto, Calif., a corporation of California

Filed May 8, 1969, Ser. No. 17,064

Term of patent 14 years

Int. Cl. D6—01

U.S. Cl. D33—8

FIG. 1 is an isometric view of a coat rack showing my new design;

FIG. 2 is an end elevational view thereof;

FIG. 3 is a front elevational view thereof; and

FIG. 4 is a bottom plan view thereof.

Both ends of the coat rack are identical.

I claim:

The ornamental design for a coat rack, as shown and described.
